UNITED STATES PATENT OFFICE.

PETER DEMETROPOULOS, OF CHICAGO, ILLINOIS.

DESIGN FOR A COMBINED CLOCK CASE AND STAND.

Application filed February 9, 1924. Serial No. 8,580. Term of patent 3½ years.

To all whom it may concern:

Be it known that I, PETER DEMETROPOULOS, a citizen of the Kingdom of Greece, who have declared my intention of becoming a citizen of the United States, residing at Chicago, Cook County, Illinois, have invented a new, original, and ornamental Design for a Combined Clock Case and Stand, of which the following is a specification, reference being had to the accompanying drawing, forming a part thereof.

The figure is a plan view of the combined clock case and stand showing my design.

I claim:

The ornamental design for a combined clock case and stand or a similar device, as shown.

PETER DEMETROPOULOS.
